Primary Examiner — Lauren D McVey*(74) Attorney, Agent, or Firm* — Jones Day(57) **CLAIM**

The ornamental design for a pen applicator, as shown and described.

DESCRIPTION

FIG. 1 is a perspective view of a first embodiment of a pen applicator in accordance with the present design;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof;

FIG. 8 is a perspective view of a second embodiment of a pen applicator in accordance with the present design;

FIG. 9 is a right side view thereof;

FIG. 10 is a left side view thereof;

FIG. 11 is a front view thereof;

FIG. 12 is a back view thereof;

FIG. 13 is a top view thereof; and,

FIG. 14 is a bottom view thereof.

The broken lines depict portions of the pen applicator that form no part of the claimed design. The “motherson innovations” lettering and icon forming part of the claimed design is a trademark of Motherson Innovations Company Ltd.

1 Claim, 12 Drawing Sheets(56)
